UNITED STATES PATENT OFFICE.

GEORGE M. WILLIAMS, OF SANTA ROSA, CALIFORNIA.

TRUCK.

SPECIFICATION forming part of Letters Patent No. 653,481, dated July 10, 1900.

Application filed January 19, 1900. Serial No. 2,023. (No model.)

To all whom it may concern:

Be it known that I, GEORGE M. WILLIAMS, a citizen of the United States, residing at Santa Rosa, in the county of Sonoma and State of California, have invented certain new and useful Improvements in Truck-Wheels; and I do hereby declare the following to be a full, clear, and exact description of the invention, such as will enable others skilled in the art to which it appertains to make and use the same.

My invention relates to certain improvements in trucks, pertaining to that class especially adapted for use in stores, warehouses, and like business places for readily moving or transporting barrels, boxes, &c.

It has for its objects principally to provide for the ready and convenient locking and unlocking of the truck-wheels as relates to their turning or non-rotation upon their axle as occasion may require, to effect the manipulation or application and disengagement of the lock, and to otherwise provide for efficiency and facility in the use of the device.

It consists of the combination, construction, and arrangement of certain parts for carrying out the foregoing objects, substantially as hereinafter more fully disclosed, and specifically pointed out in the claims.

It will be understood that latitude is allowed herein as to details, as they may be changed or varied according to circumstances without departing from the spirit of my invention and the same yet remain intact and be protected.

In the accompanying drawings, illustrating the preferred embodiment of my invention, Figure 1 is a longitudinal section. Fig. 2 is a broken sectional view. Fig. 3 is a rear underneath view. Figs. 4 and 5 are views of a modification of the invention.

In carrying out my invention I employ a truck 1 of the character above described, in its general construction such as ordinarily used, and in connection therewith use a brake or lock for the relative locking and unlocking of the wheels 2. This lock comprises a transverse sliding or movable bar 3, adapted to engage said wheels especially designed therefor, as presently seen, and arranged or supported in position in slotted or skeleton castings or brackets 4, adapted to be conveniently secured to the truck-frame upon its under side. The sliding or locking bar 3 has its end por-

tion relatively reduced, if necessary, to enter radial sockets or notches formed by providing the truck-wheels upon the inner side each 55 with a circular series or arrangement of projections or lugs 5 at the periphery, with their rims closing said sockets or notches at that point. Said sliding or locking bar has also at the points of conjunction between its reduced end portions and its body portion lugs or projections 6 to prevent it from jamming or binding upon the spokes of the wheels, as it were, as would be liable to otherwise occur. This bar or brake is adapted to be held automatically in engagement with the notches or 65 sockets of the truck-wheels when it is desired to prevent the latter from turning on the axle by means of springs 7, coiled or helical, secured or connected to the truck-frame and 70 said bar, respectively.

A cylindric bar or rod 8, carrying catches 9 at a suitable interval apart, has its ends let into sockets or eyes 8^a on the castings or brackets 4 to turn therein, and connected to 75 said rod near one end and the truck-frame is a spring 9^a, coiled or helical, the function of which will presently appear. The rod or bar 8 has also a trip or projection 10 near its opposite end to provide for its convenient actuation by the foot or otherwise.

It will be seen that when the locking-bar 3 is withdrawn or disengaged from the radial or lateral notches or sockets of the truck-wheels, which is effected by pressing downward upon said bar sufficiently to overcome the resistance of its springs, it (said bar) will be caused to pass into contact with the beveled upper portions of the catches 9 and below said catches. During such passage of 90 said bar the catches yield and instantly or automatically catch over the latter under the action of the spring applied to the rod carrying said catches, and thus hold said bar out of engagement with the truck-wheels. Of course 95 in order to again effect engagement of the locking-bar with the truck-wheels it is only required that sufficient pressure be applied by the foot or otherwise to the catch-carrying rod through the trip or lug 10^a thereof, said 100 rod turning on its axes and permitting the catches to be disengaged from said bar, allowing the latter to be automatically moved or slid into engagement with the wheel-notches

under the action of its springs, as above intimated.

The locking of the truck-wheels, as is desirable when loading upon the truck whatever weight or heavy body it may be required to move or transport thereon, aids to prevent the involuntary slipping or movement of the truck, though braced by the foot or body, or both, of the person using it, as well understood.

In the modification, as disclosed in Figs. 4 and 5, I may employ an arched locking-bar 11 to provide greater space for the application of the foot to the truck-wheel, axle as in loading the truck, and to this bar is suitably connected, as shown or otherwise, a guide-bar 12, adapted to enter the contracted portions of the preferably skeleton brackets or castings 13. Springs 14, suitably connected to the truck-frame or bracket and to said locking-bar, are employed for effecting the automatic holding of said bar in engagement with the truck-wheels or their sockets or notches above referred to. To overcome the resistance of these springs in disengaging said bar from the truck-wheel notches or sockets, the foot is applied to said bar. In order to hold said bar out of such engagement, the guiding-bar 12, connected thereto, is caused to engage the downward-facing shoulders 15 at the lower ends of the contracted portions of the slots of the brackets or castings 13, aided, if necessary, by the action of an additional spring (not shown) suitably connected to the truck-frame or brackets and disposed or arranged to bear upon said guide-bar. Said locking-bar is provided with a trip or projection 17, which is more especially designed to provide for retracting or disengaging the guide-bar 12 from the shoulder 15, preferably by the application of the foot thereto, when it is desired to engage the locking-bar with the wheels.

The cylindrical bar or rod 8, with the catches 9, the castings or brackets 4, with eyes 8^a, and the parts for the manipulation of the same in general, as heretofore described, may be used

when desired in connection with the arched locking-bar 11. In other words, any desired part of one truck may be used in the make-up of any other truck, if preferred.

Having thus fully described my invention, what I claim, and desire to secure by Letters Patent, is—

1. A truck of the character described, having its wheels each provided with a circular series of notches or sockets near its periphery, guide-brackets, and a sliding bar having shoulders adapted to engage said guide-brackets, said bar also adapted to engage said notches or sockets, substantially as set forth. 55

2. A truck of the character described, having a sliding bar adapted to be automatically held in locking engagement with its wheels, and a locking device for holding said bar disengaged from said wheels when not in use, substantially as specified. 60

3. A truck of the character described, having a sliding bar adapted to engage its wheels and a rocking bar or rod having catches adapted to engage said sliding bar, substantially as set forth. 70

4. A truck of the character described, having slotted brackets or castings, a spring-pressed sliding bar adapted to engage and lock the truck-wheels relatively to the axle, a spring-pressed rocking bar or rod having catches adapted to engage said sliding bar, substantially as set forth. 75

5. A truck of the character described, having slotted brackets or castings, a spring-pressed sliding bar adapted to engage and lock the truck-wheels relatively to the axle, a spring-pressed rocking bar or rod hung in said brackets and having bevel-ended catches 80 adapted to engage said sliding bar, substantially as set forth. 85

In testimony whereof I affix my signature in presence of two witnesses.

GEORGE M. WILLIAMS.
